SELECTOR ARRANGEMENT FOR THE SELECTIVE CALL OF TELEPHONE SUBSCRIBER STATIONS FOR THE PRIVATE AND OFFICIAL EXCHANGE

Otto Moser, Bern, Switzerland

Application March 29, 1934, Serial No. 718,056
In Switzerland March 29, 1933

1 Claim. (Cl. 179—16)

The present invention relates to a selector arrangement for a direct call telephone system.

In direct call telephone systems push button line finder devices have been employed for many 5 years. These are subscriber's instruments which, as expressed by their name, are equipped with push button switches which render it possible to call and to speak to any subscriber's station of the system by pressing on the respective press 10 button.

Every single subscriber's instrument must be provided with so many push button switches as there are stations which wish to be able to call 15 one another directly. If the system has five such stations there must be provided for each subscriber's instrument five switches and ten switches if there are ten stations and so on. If the system is connected to a public telephone system as is common to-day, the instruments are provided in 20 addition according to the number of service connections with one, two, three or more push button switches for making connection with the external exchange. If the external exchange is automatic there must be added also the rotary selectors. 25 Therefore, on such line finder instruments, three different kinds of switches are present; the push button switches for the direct call system, the push button switches for making connection with the external exchange and the rotary selectors. 30 The operation of the instruments is, therefore, tedious and the manufacture thereof is expensive. To simplify matters special push button switches, mechanically-coupled together have been provided and to reduce the manufacturing costs es- 35 pecially in recent years it has been endeavoured to construct switches as compactly and cheaply as possible. The number of push buttons has, however, remained the same and, in spite of all improvements, in order to locate these buttons 40 it is still necessary to construct apparatus varying in size and arrangement according to the number of connections of the line finder system.

The present invention provides a system in 45 which the push button switches for permitting direct calls are rendered unnecessary. The only switches necessary are those for the external exchange. The whole line finder mechanism may be located in the casing of a normal subscriber's telephone instrument. The internal construction 50 of the instruments has been simplified and the operation of the switches improved.

The invention is illustrated by way of example 55 in the accompanying drawings in which Fig. 1 illustrates diagrammatically a direct call system embodying the invention. Each subscriber's sta-

tion is equipped with a small rotary selector W similar to those used in connection with automatic telephone systems.

The selector is operated by the finger disc N. When the number 1 is dialled on the finger disc, 5 the contact arms of the selector will move to the position 1; if the number 2 is dialled the contact arms of the selector will execute two steps and so on. In this manner the connection with the desired station will be established over the various 10 lines connecting the individual subscriber's instruments. But since the finger disc N is also needed for establishing connection with the public system, if this is of the automatic exchange type, the coupling K between the finger disc and 15 the selector is arranged to be cut out, when an exchange key A is operated. The contact brushes of the selector at the subscriber's station will not then be advanced but will remain in the position of rest. It may now become necessary to speak 20 with the internal stations of the direct call system whilst external calls are being sent or received. For this purpose the coupling K between the finger disc and the selector is re-inserted as soon as the exchange key is brought into a hold- 25 ing position, i. e., a position in which internal calls may be made without disconnecting the instrument from the exchange. In order to permit the operator to make any number of internal calls 30 in this position of the exchange key the contact brushes of the selector are arranged to return to their position of rest each time the finger disc is operated for an internal call.

The manner in which these various operating 35 conditions are attained will be seen from Figures 2 and 3. The finger disc N is coupled with the line finder system by means of the two pins b1 and b2 of the coupling wheel Ba. When the telephone is put down at rest a button HU presses through 40 the intermediary of a lever A upon a pawl C secured to the coupling wheel Ba, so that this pawl, when the finger disc turns the wheel Ba coupled therewith, will pass a pin D provided on an inner coupling wheel B1.

The rotary selector will, therefore, remain in 45 its position of rest if the finger disc is operated with the telephone on its hook. If the telephone is removed the lever A is withdrawn from the pawl C by the spring L and this pawl is moved inwards by spring E. As soon as the finger disc 50 is operated the pawl C pushes against the pin D so that the inner wheel B1 is also rotated and in turn rotates the wheel W of the rotary selector. The selector brushes W₁, W₂, W₃ will, according to the number dialled on the finger disc, 55

be adjusted to the contacts 1, 2, 3 etc. on the selector contact bank M and thereby to the line of the selected subscriber's station. The desired connection is thus established. Upon the return of the finger disc the wheel Ba will return into its position of rest. If, at the end of the conversation, the telephone is replaced a pawl S will be withdrawn from the teeth of the wheel W by means of an auxiliary arm F of the lever and the wheel W and the brushes will be moved back into rest position by a spring O.

It is also possible to make a number of internal calls successively without replacing the telephone each time. When the finger disc is again operated at the beginning of the rotary movement, the resilient mask Q causes the coupling K to be pressed against the arm F which will withdraw the pawl S from the teeth of the wheel W and the selector will turn as described into the position of rest. When the dialling is continued the selector brushes will again be adjusted according to the number dialled and so on.

For establishing or answering an external call an exchange key has to be operated. This moves levers X and G so that the latter presses against a pin J causing lever A to be pressed against the pawl C and the selector remains in the position of rest.

If in connection with the external call an internal station has to be called the holding key has to be operated. The exchange key will be moved thereby into the holding position. The two lever arms X and G release the lever F and the pawl G can then cause, as described, the selector wheel to rotate and several internal calls may be successively effected without replacing the telephone. If the telephone is replaced the exchange key and the selector brushes return to their positions of rest.

The above-mentioned exchange and holding keys are represented diagrammatically in Figures 2 and 3 at P and V respectively. There

are three exchange keys each of which is connected to the external exchange.

To call the exchange an unoccupied key P is pressed down to position Z and if it is desired to make an internal call without disconnecting from the exchange the key V is then pressed down. This will cause the key P to be raised to the position Y. This movement of the key P is transmitted by lever X to lever G so that the lever F is released as above described and a number of internal calls may be made. Whilst the key P is in the position Y it will maintain the connection to the exchange but without transmitting the internal conversation to the exchange.

To continue the conversation with the exchange, key P is again pressed down into position Z. When the telephone is replaced the key P will return to its original position.

I claim:—

In a selector arrangement for a direct call telephone system, where a dialling mechanism may be selectively connected for internal and external exchanges and in combination, a telephone rest arranged as a push button, a dialling mechanism comprising a driving shaft and a coupling disk having coupling pins and fast to this shaft, a finger disk coupled to said shaft by said pins, a gear provided with a carrier pin loose on said shaft and a spring controlled pawl fast to said coupling disk and adapted to be engaged with said carrier pin, a line finder mechanism comprising a spring controlled auxiliary shaft, a toothed selector wheel meshing with the gear on the driving shaft and selector brushes both fast to this shaft and contact banks in reach of said brushes, external exchange keys and a holding and counter question key and a lever arrangement adapted to establish the operating positions of the line finder mechanism for the different positions of the exchange keys.

OTTO MOSER.
